(No Model.)

W. A. LEWIS.
CONTROLLING BRIDLE FOR HORSES.

No. 515,593.

Patented Feb. 27, 1894.

UNITED STATES PATENT OFFICE.

WILLIAM A. LEWIS, OF COLUMBUS, OHIO.

CONTROLLING-BRIDLE FOR HORSES.

SPECIFICATION forming part of Letters Patent No. 515,593, dated February 27, 1894.

Application filed September 25, 1893. Serial No. 486,411. (No model.)

To all whom it may concern:

Be it known that I, WILLIAM A. LEWIS, a citizen of the United States, residing at Columbus, Franklin county, Ohio, have invented 5 new and useful Improvements in Controlling-Bridles for Horses, &c., of which the following is a specification.

My invention relates to bridles for horses: its object being to produce a bridle for controlling high spirited or vicious animals, and particularly restless, indifferent, or callous-mouthed-animals imperfectly broken to the ordinary mouth-bit.

To this end it consists in a bridle embodying, 15 in combination, a head-stall adjusted to the head, and secured under the neck; a "chin-clamp," and lead ropes or reins secured to the head stall and passing through the mouth of the animal and engaging the chin-clamp in 20 such a manner as to serve as a mouth-bit: whereby any pull upon the reins—either by the act of the animal in throwing up the head contrary to the tension of the reins, or by the act of the driver directly,—produces a tightening 25 of the chin-clamp at the rear of the under-jaw,—giving a powerful and certain control of the animal without injury.

My invention is illustrated in the accompanying drawings exhibiting in Figure 1, a front 30 perspective elevation of my controlling bridle; Fig. 2, a perspective side elevation: Fig. 3, an enlarged perspective view of the chin-clamp detached: showing construction: and Fig. 4, a side elevation showing the action of 35 the bridle in use.

Referring now more particularly to the drawings,—A, designates the head-stall or "crown piece," of my improved bridle: a, the forehead strap or "browband" and, a', the 40 neck-strap or "throat-latch." These parts are constructed and arranged as in ordinary bridles, and require no further description. In lieu however of the ordinary bit, the ends of the head-stall are attached to a "chin-clamp," B, constructed as follows:

The chin-clamp consists of a substantially semi-circular bar, b, provided with an offset parallel guide bar, b', forming a guide loop at 45 rear of the midportion or "bight" of the arc: and terminating at the front in cheek-pieces, b², extending in parallel relations downwardly

perpendicular to the general plane of the bar, b. The cheek-pieces, b², terminate below in circular loops, b³, and are provided exteriorly with rectangular loops, b⁴, and an intervening 55 stud, b⁵, projecting outward from the face of the cheek-piece, for engagement of the head-stall, A, adjustably, as provided by the series of apertures, z, in the latter for engaging over the stud. The loops, b³, being thus located 60 below the general plane of the curved bar, b, it will be seen that (the latter being suspended horizontally at its cheek pieces by the head-stall) a forward or backward pull upon the loops, b³, will cause the rear portion or "bight" 65 of the curved bar to traverse a vertical arc of which the cheek-pieces are at the pivotal center.

At each of the inner sides of the headstall, A, is attached one end of a lead-rein, R,— 70 which passes thence downward through the guide aperture formed by the guide bar, b', and crosses over and out through the opposite loop, b³, of the chin-clamp. The reins, R,— which may be a single continuous strap or 75 rope—are preferably attached to the head-stall by a section or elastic band, r. The bridle is placed over and secured to the animal in the usual manner, and the chin-clamp, B, adjusted so that the bar, b, lies behind and 80 against the under jaw of the horse, in such relation that the reins, passed downward and through the opposite loops of the chin-clamp, pass first in opposite directions through the mouth of the animal in the place ordinarily 85 occupied by a "bit."

The action of the bridle will be understood from Fig. 4 wherein it will be seen that upon pulling the bridle reins, and taking up the "slack," the angle of the reins in passing 90 through the rear guide and through the lower loops, causes the curved bar, b, of the chin-clamp to tilt upward in relation to the cheek-pieces as centers of oscillation and bear against the rear side of the under jaw; while 95 the reins complete the circle around said jaw through the mouth and thus produce a powerful compression (like that of a ligature) causing more or less temporary pain without permanent injury. By shortening the head- 100 stall attachment of the cheek-pieces, b², the reins are made to bear more directly inward in

the mouth against the angle of the lips, and the action of the bridle is made thereby more severe; but generally, it is sufficient to make the adjustment so low down as to avoid all danger of cutting or abrading the lips, and rely entirely on the clamping action upon the jaw. In either case the elastic connections, 5, modify the direct action of the device and avoid all injury.

10 I claim as my invention and desire to secure by Letters Patent of the United States—

15 1. The improved bridle, embodying in combination a head-stall; a chin-clamp attached thereto and encircling the rear of the lower jaw; and lead reins attached to the head-stall and crossing downward through a guide at the rear of the chin-clamp and outward and

through opposite lower loops at the ends of the chin-clamp substantially as set forth.

20 2. In a controlling bridle, a metal chin-clamp, embodying two side or cheek-pieces for the attachment of a head stall, terminating below in loops for the passage of the bridle reins and united rearwardly by a curved bar having a second parallel bar attached forming 25 an extended loop for the passage of the bridle reins, substantially as set forth.

In testimony whereof I have hereunto set my hand in the presence of two subscribing witnesses.

WILLIAM A. LEWIS.
